UNITED STATES PATENT OFFICE.

JOHN H. DAMON, OF PLYMOUTH, MASSACHUSETTS, ASSIGNOR TO PLYMOUTH CORDAGE COMPANY, OF PLYMOUTH, MASSACHUSETTS, A CORPORATION OF MASSACHUSETTS.

BALL OF BINDER TWINE AND APPARATUS FOR PRODUCING THE SAME.

Application filed November 2, 1925. Serial No. 66,174.

This invention relates to improvements in balls of binder twine and apparatus for producing the same. Owing to the characteristic wiry and stiff nature of the fibers of 5 hemp from which binder twine is made the twine has fibers projecting from it in all directions to a distance equalling the greater part of an inch and even more in many cases. It is the custom of some makers to 10 wind this twine into a ball or mass in the nature of a cylindrical cop having a plane end, in which the plane end is made by the characteristic of the winding machine that brings each movement of the thread guide 15 to the plane and then backward toward the other end of the cop. These balls have advantages because of the superior density with which they can be wound and the superior uniformity of size, dimension and 20 shape; but the individual fibers projecting from those threads which are exposed at the end of the cop make a forest of small hairs or fibers projecting from the end of the package. The present invention provides 25 means by which to a great extent these projecting fiber ends are turned inward and bound under the threads in the package. Thereby two effects are gained; the end aspect of the cop is greatly improved by being given a smooth and finished appearance; and there is to some extent a binding effect 30 of these turned-in fibers, which contribute toward holding the ends of the package in better shape by constituting a multitude of 35 small anchors applied to the exposed portions of each thread at the end of the wound mass. This said anchorage serves conversely to hold those fibers in the midst of the package, instead of letting them project. 40 The package produced by the invention is like those which have been formerly produced; except that to a great extent the fibers which in the former package have been outstanding from the end are turned 45 in and embedded in the package; the few which may remain having for one reason or another missed the operation of the wipers hereinafter described.

The invention relates to the production 50 of a mass with its end fibers thus turned in and the provision of machinery by which this effect can be gained by attachments on the ordinary package winding machine. These are in the nature of wipers, one being adapted to engage the package at each

end. Each wiper has an end bearing surface and a surface reaching in a little way from the end with bearing on the cylindrical side of the mass which is in process of being wound. As applied to the ordinary machine, 55 the attachment embodies an arm with a vertical side surface and with a horizontal finger. The vertical face engaging the end of the package tends to direct the projecting fibers in toward the body of the package when the, 60 said package is rotated; and the finger projecting inward therefrom and resting on the periphery of the package is adapted to pass over the fibers thus turned inward and retain them upon the body of the package 65 until the same are permanently secured by the next succeeding thread being wound thereupon, which thread is laid in close proximity. In this manner the package 70 when complete is rid of the vast amount of 75 projecting fibers at its ends, there being but comparatively few which escape the binding operation; and the general appearance 80 of the package is greatly improved. And the ends of the package are to a degree 85 strengthened by the tendency of the in-turned fibers to anchor the exposed end portions of the threads to prevent slippage of those loop parts of the thread whose yielding produces looseness and permits collapse 90 of the mass or even is liable to cause it.

One form of the invention is illustrated 95 in the accompanying drawings. It is intended that the patent shall cover by suitable expression in the appended claims 100 whatever features of patentable novelty exist in the invention disclosed.

In the accompanying drawings:

Figure 1 is a side elevation of what is 95 commonly known as a universal wound package, showing the invention applied;

Figure 2 is an end view of the same;

Figure 3 is an elevation in section through 100 a detail of the device of the invention, illustrating the position of the same upon a package;

Figure 4 is a perspective view illustrating 105 the approach of the wiper to projecting fibers;

Figure 5 is a similar view illustrating the manner in which the vertical face of the wiper engages fibers, directing them inward; and

Figure 6 is a similar view illustrating the manner in which the horizontal finger en- 110

gages the inward turned fibers, holding them in position until bound underneath the next succeeding strand which is also seen approaching.

- 5 In the drawings the numeral 10 indicates a conventional compact cop or universal-wound package of binder twine, between whose ends 12 12 travels the reciprocating guide 14 for positioning the strand upon the package as it is wound. Arms 16, supported from the frame of the winding machine, are positioned at the ends of the package with the flat face of each lying in a vertical plane at the end of the package 15 near the periphery thereof, so that fibers projecting endwise from the mass beyond that plane are turned back inward. Each arm 16 also carries an inward extending finger 18 which lies horizontally upon the periphery of the package, each said finger being substantially flat. Both of these rest lightly against or close to their respective surfaces of the mass, no great pressure being requisite. As the mass is rotated in the winding operation the projecting fibers 20 at the end of the package encounter the faces 16 which turn them inward as illustrated in Figure 5 of the drawings; and as the package turns further in its rotating motion the said inward turned fibers pass under the horizontal fingers 18 as shown in Figure 6, which bend them down to positions close to the cylindrical surface. While the fibers are thus held in position by the fingers 18 30 the thread 22 is laid over them close to their root ends. They are thus securely held upon the body of the package and with the laying of later threads will be hidden from view. Fibers so bound within the body of the

package will tend to anchor the portions of 40 thread to which they are attached, so that the parts near the end of the package have less likelihood of working loose, or of being loosened by a shock or blow, thus strengthening the cop or package at its ends as well 45 as improving the outward appearance of the ends.

I claim as my invention:

1. In the art of winding binder twine into a cylindrical mass, the bending of the 50 endwise projecting fibers to position over the cylindrical surface of the mass and holding them there in the path of twine which is being wound, thus causing the said fibers to be bound within the body of the 55 mass.

2. Means for directing the endwise projecting fibers, during the winding of a mass of binder twine, comprising an element set close against the end of the package at the 60 periphery thereof and adapted to bend the endwise projecting fibers backward over the cylindrical surface whereon the winding is proceeding; and a finger overlying said cylindrical surface for holding the said bent 65 fibers close to the cylindrical surface of the mass until bound thereon by the thread which is being laid in the said winding operation.

3. An improved package of binder twine 70 in which those fibers which tend to protrude from the ends of the wound cylindrical mass are bent over and bound between adjacent layers of the cylindrical mass.

Signed at Plymouth, Massachusetts, this 75 twenty-third day of October, 1925.

JOHN H. DAMON.
